(57) **CLAIM**

The ornamental design for lid for drink bottle having back button released cover and carry loop, as shown and described.

DESCRIPTION

FIG. 1 is a perspective view taken from the upper, front, right-hand side of the lid for drink bottle having back button released cover and carry loop of the present invention;

FIG. 2 is a perspective view taken from the lower, back, left-hand side of the lid for drink bottle having back button released cover and carry loop of FIG. 1;

FIG. 3 is a side elevational view of the left side of the lid for drink bottle having back button released cover and carry loop of FIG. 1;

FIG. 4 is a front elevational view of the lid for drink bottle having back button released cover and carry loop of FIG. 1; FIG. 5 is a side elevational view of the right side of the lid for drink bottle having back button released cover and carry loop of FIG. 1;

FIG. 6 is a rear elevational view of the lid for drink bottle having back button released cover and carry loop of FIG. 1; FIG. 7 is a top plan view of the lid for drink bottle having back button released cover and carry loop of FIG. 1; and, FIG. 8 is a bottom plan view of the lid for drink bottle having back button released cover and carry loop of FIG. 1.

The broken lines showing in the figures are included for the purpose of illustrating portions of the lid for drink bottle having back button released cover and carry loop that form no part of the claimed design.
